UNITED STATES PATENT OFFICE.

WILLIAM H. GERNS, OF EAST ORANGE, NEW JERSEY, ASSIGNOR TO BRANDES LABORATORIES, INC., OF NEWARK, NEW JERSEY, A CORPORATION OF NEW JERSEY.

ELECTROMAGNETIC DRIVER.

Application filed November 28, 1925. Serial No. 71,930.

My invention relates broadly to the reproduction of sound from electrical vibrations and more particularly to the construction of an electromagnetic driver for sound reproducers.

One of the objects of my invention is to provide an electromagnetic driver for sound reproducers which is capable of developing vibrations of relatively large amplitude from electrical vibrations by reason of an opposed relationship of a pair of electromagnetic systems arranged to operate upon the same armature.

Another object of my invention is to provide a construction of armature for an electromagnetic driver of the double magnetic type where the armature provides means for positively spacing the electromagnetic systems one from another and has the necessary resiliency imparted thereto by reason of its characteristic shape with means for taking off the mechanical vibrations from the armature for driving a sound reproducing diaphragm.

Still another object of my invention is to provide a construction of armature for a double magnetic type of electromagnetic sound reproducer, in which the armature is formed from a flat plate of magnetic material armatured in the shape of a plurality of sectors and a semi-circle for imparting a desired degree of resiliency to the armature and providing a proper distribution of magnetic lines therethrough.

A further object of my invention is to provide a construction of armature for a double magnetic construction of electromagnetic driver, in which the armature may be stamped from a flat sheet of magnetic material with a diametrical bridge member, which is subjected to the vibratory action of the electromagnetic system and a radial portion of which is shaped to provide means for delivering the vibrations thus produced upon a sound reproducing diaphragm.

My invention will be more clearly understood by reference to the following specification and the accompanying drawings, in which:—

Figure 1 is an end view, showing the arrangement of parts of the electromagnetic driver; Fig. 2 is a cross-sectional view taken through the double magnetic electromagnetic driver; Fig. 3 is a cross-sectional view through the driver taken on line 3—3 of Fig.

1; Fig. 4 is a plan view showing the construction of the armature used in the electromagnetic driver of my invention; and Figs. 5, 6 and 7 show modified channel sections on lines 5, 6 and 7 of Fig. 4, of the member through which mechanical vibrations are imparted to a sound reproducing surface.

Referring to the drawings in more detail reference character 1 designates a casing for an electromagnetic sound reproducer which is aligned with an oppositely positioned casing 2 of an electromagnetic sound reproducer secured together by means of bolt members 3. Permanent magnets 4 and 5 are mounted adjacent each of the casings 1 and 2 and have sets of pole pieces 6 and 7 secured thereto. The pole pieces 6 and 7 are provided with electromagnetic windings 8 and 9, by which magnetic forces are imparted to the armature 10. Alternate attractive and repulsive forces may be applied to the armature 10, thereby increasing the amplitude of movement of the armature and correspondingly the volume of the reproduced sound. The armature construction forms the particular feature of my invention. The armature is punched from a flat sheet of magnetic material in such manner as to provide apertures 3^a, adjacent the circumference thereof, by which the armature is maintained in position by bolt members 3 and serves as a spacing means for casings 1 and 2. The armature 10 is apertured in a plurality of segments, represented at 11 and 12 and in a semi-circular portion, represented at 14. The segments 11 and 12 are substantially quadrant and are positioned on opposite sides of a radial bridge-like portion 15. The segmental apertures 11 and 12 lie adjacent the semi-circular aperture 14 on opposite sides of the diametrical portion 16, which forms the principal area which is subjected to the magnetic lines of force emanating from pole pieces 6 and 7. The bridge-like member 15 is pressed in such manner that side portions 17 and 18 extend upwardly therefrom in the form of a channel, as represented more clearly in Fig. 7. In Fig. 6, I have shown the side portions 17 and 18 bent into a circular shape 19 to grip a hook shaped end 20 of rod member 21, by which mechanical vibrations developed by the armature may be conveyed to a sound reproducing diaphragm. In Fig. 5, the sides 11^a

portions 17 and 18 may be bent only partially into a circular shape, leaving a gap 22 between adjacent ends of the side portions 17 and 18. The shape being such, however, 5 that the hook shaped end 20 of the rod member 21 may be readily gripped therein.

The armature member, by reason of its apertured portions, has a high degree of resiliency and may be actuated by magnetic forces delivered by the electromagnetic system with minimum inertia. The location of the rod member 21 on the bridge member 15 is such that mechanical vibrations may be impressed upon a sound reproducing diaphragm with a high degree of efficiency. The construction of the armature in the manner illustrated facilitates manufacture of the electromagnetic sound reproducer. The electromagnetic driving unit lends itself particularly well as an actuator in a cone speaker, where the rod member 21 connects with the apex of a conical diaphragm and positively moves the cone in opposite directions, by virtue of the attraction and repulsion offered by the double electromagnetic system.

While I have illustrated the armature construction in certain preferred embodiments, I desire that it be understood that 30 modifications may be made and that no limitations upon the invention are intended other than are imposed by the scope of the appended claims.

What I claim and desire to secure by Letters Patent of the United States is as follows:

1. In an electromagnetic driver, a sound reproducing diaphragm, a pair of electromagnetic driving units positioned opposite each other, an armature positioned between said electromagnetic driving units, said armature comprising a flat sheet of magnetic material apertured in a plurality of segments one of which is substantially semi-circular, a band extending between each of said segments, one of said bands being directly actuated by attractive and repulsive forces of said electromagnetic driving units and the other of said bands being arranged 50 to deliver mechanical vibrations from said armature to said sound reproducing diaphragm.

2. In an electromagnetic sound reproducer, the combination of a pair of independent electromagnetic drivers each having pole pieces directed toward each other, a sound reproducing diaphragm, a circular armature member positioned between said drivers, and having a diametrically extending band across the center thereof arranged to be actuated by attractive and repulsive forces from said pole pieces, and a bridge member disposed between said band, and one side of said circular armature member, 65 whereby mechanical forces set up in said

band may be transmitted to said bridge member, for actuating said sound reproducing diaphragm.

3. In an electromagnetic sound reproducer, the combination of a pair of independent electromagnetic drivers each having pole pieces directed toward each other, a sound reproducing diaphragm, a circular armature member positioned between said drivers, said circular armature member comprising a flat sheet of magnetic material apertured in a plurality of segments, with each of said segments separated by bands of relatively different widths, said armature member being arranged to receive mechanical vibrations along one of said bands and transfer mechanical vibrations to said sound reproducing diaphragm along another band.

4. In an electromagnetic sound reproducer, the combination of a pair of independent electromagnetic drivers each having pole pieces directed toward each other, a sound reproducing diaphragm, a circular armature member positioned between said drivers, said circular armature member being apertured to form a pair of band members directed at right angles to each other, with one of said band members extending diametrically across said circular armature member and the other of said band members extending radially across said circular armature member from said first-mentioned band member, whereby repulsive and attractive forces set up in said first mentioned band member may be conveyed to said second mentioned band member for actuating said sound reproducing diaphragm.

5. In an electromagnetic sound reproducer, the combination of a pair of independent electromagnetic drivers each having pole pieces directed toward each other, a sound reproducing diaphragm, a circular armature member positioned between said drivers, said circular armature member being apertured in three segmental parts, forming a narrow band and a relatively wide band therebetween, with the relatively wide band extending diametrically of said armature and the relatively narrow band extending radially of said armature between said relatively wide band and the outer periphery of said circular armature member, whereby mechanical forces set up in said relatively wide band may be imparted to said relatively narrow band for actuating said sound reproducing diaphragm.

6. In an electromagnetic sound reproducer, the combination of a pair of independent electromagnetic drivers each having pole pieces directed toward each other, a sound reproducing diaphragm, a circular armature member positioned between said drivers, said circular armature member being apertured in a plurality of segmental

- shapes, with a relatively wide band extending diametrically across said armature and a relatively narrow band interconnecting the center of said band and the outer periphery of said circular armature member, said relatively narrow band being channel shaped in cross-section, and means connected between said channel shaped relatively narrow band and said sound reproducing diaphragm, whereby mechanical vibrations set up in said relatively wide band are transferred to said sound reproducing diaphragm through said relatively narrow band.
- 5 7. In an electromagnetic sound reproducer, the combination of a pair of independent electromagnetic drivers each having pole pieces directed toward each other, a sound reproducing diaphragm, a circular armature member positioned between said drivers, said circular armature member being formed into a pair of integral band por-
- tions, one disposed at right angles to the other, one of said band members being actuated by said electromagnetic drivers, 25 and the other of said band members being mechanically vibrated from said first mentioned band member.
8. In an electromagnetic sound reproducer, the combination of a pair of independent electromagnetic drivers each having pole pieces directed toward each other, 30 a sound reproducing diaphragm, a circular armature member positioned between said drivers, said circular armature member having a pair of strip like portions disposed at right angles to each other, one of said strip like portions being actuated by said electromagnetic drivers, and the other of said strip like portions being arranged to impart 35 mechanical vibrations to said sound reproducing diaphragm.
